GLASS COMPORT OR SIMILAR ARTICLE

Horace King, Granville, Ohio, assignor to A. H.
Heisey & Company, Newark, Ohio

Application May 9, 1951, Serial No. 15,109

Term of patent 3½ years

(Cl. D36—2)

To all whom it may concern:

Be it known that I, Horace King, a citizen of the United States of America and a resident of Granville, in the county of Licking and State of Ohio, have invented a new, original, and ornamental Design for a Glass Comport or Similar Article, of which the following is the specification, reference being had to the accompanying drawing, forming a part hereof.

Figure 1 is a perspective view of a glass comport or similar article, showing my new design.

Figure 2 is a cross sectional view of the stem taken along line 2—2 of Figure 1.

Figure 3 is a partial vertical sectional view taken along line 3—3 of Figure 1.

Figure 4 is a top plan view of the article shown in Figure 1.

The dominant feature of my design resides in the bowl portion and its relation and association with the remaining portions thereof.

I claim:

The ornamental design for a glass comport or similar article, substantially as shown and described.

HORACE KING.
